UNITED STATES PATENT OFFICE.

JOHN F. FARRINGTON, OF FLUSHING, NEW YORK, ASSIGNOR TO WESTERN ELECTRIC COMPANY, INCORPORATED, OF NEW YORK, N. Y., A CORPORATION OF NEW YORK.

TWO-WAY WAVE TRANSMISSION SYSTEM.

Application filed December 29, 1923. Serial No. 683,395.

This invention relates to duplex transmitting methods and systems and, more particularly, to methods of and apparatus for simultaneous telephony and telegraphy.

It is an improvement in the system disclosed in my application filed December 24, 1920, Serial No. 432,900. In the method of that application an additional telegraph communication channel is superposed on a difference frequency two-way telephone system of the type disclosed in British Patent 186,946, accepted October 5, 1922. This is accomplished by varying the frequency of the transmitted carrier by an audible amount in accordance with a telegraph code and thereby varying the detected difference frequency accordingly. A local receiver source, producing waves of the normal difference frequency is used. Waves from this source are combined with the detected difference frequency wave. When telegraph signals are being sent the combination wave contains a component having a frequency equal to the change in carrier frequency. An indicator is placed across the output of the combining device. When no telegraph signal is being sent there is no wave impressed on the indicator or in other words the frequency is zero. When the incoming or outgoing carrier is changed to transmit telegraph impulses there is a tone impressed on the indicator. The telegraph channel of the system of my said application operates, therefore, in a manner similar to that of the Farrington or difference frequency method, and the operation as in that method, is characterized by reception of both the distant and local telegraph signals in the telegraph receiver. However, if simultaneous duplex telegraphy were attempted the telegraph beat frequency would be a composite of the telegraph frequencies transmitted simultaneously from both stations; that is, the telegraph messages would be superposed and render simultaneous duplex transmission impracticable.

In accordance with the present invention means is provided in association with the circuit arrangement of my said application whereby the frequency of the local telegraph source is made to vary with the variations of outgoing carrier frequency during telegraph transmission, whereby the side tone is eliminated and since this arrangement removes the effect in the telegraph re-

ceiver of the change in frequency of the outgoing carrier, it makes this receiver responsive to changes in the incoming carrier only. Therefore, the receiving operator can hear in his receiver the incoming telegraph message only and may receive this message and simultaneously transmit a message without the slightest interference between the oppositely directed transmissions.

The single figure of the drawing illustrates a system embodying one form of the invention.

Referring to the drawing, a constant current modulating system 1, having an oscillator O of well-known type, is shown arranged for radio telephone transmission. The modulation system is of the type disclosed in U. S. Patent to R. A. Heising No. 1,537,941, May 19, 1925, although other systems of modulation could equally well be used. The antenna is broadly tuned to the frequency f_1 of the oscillations produced by oscillator O and therefore serves to transmit oscillations of frequencies $f_1 \pm S_1$ and f_1 , representing, respectively, the side bands and the unmodulated carrier component of speech modulated outgoing carrier waves. The frequency of the speech waves at this station is represented by S_1 . In order to change the carrier frequency f_1 for code signaling a key K is provided to operate a relay 4 which at its left armature short circuits a reactance R in the frequency determining circuit of the oscillator O to vary the carrier frequency by an audible amount, for example, 150 cycles.

The distant station, not shown, has similar transmitting apparatus, except that its oscillator produces waves of frequency f_2 and accordingly transmits to the station shown oscillations of frequencies $f_2 \pm S_2$ and f_2 , representing, respectively, the modulated side bands and unmodulated carrier frequency component, S_2 , denoting the frequency of speech waves to be transmitted from the distant station. The frequencies f_1 and f_2 differ by an amount preferably in the range above good audibility. In order efficiently to select and receive the incoming waves, the antenna is provided with an additional path 3 tuned, in conjunction with the transmitting antenna circuit, to the mean frequency of the received waves. This path includes a loop E anti-resonant at the frequency f_1 and accordingly passes little cur-

rent of the outgoing carrier frequency. A slight amount of the energy of the outgoing transmitted frequency finds its way through this path and is applied with the received waves to the input circuit of a high frequency detector HFD. This produces in the output circuit of the detector a complex current of which there is a component having a frequency equal to the inaudible difference frequency of the two carrier waves. During outgoing speech transmission, this inaudible difference or intermediate frequency component is modulated by waves of frequency S_1 and during incoming speech transmission by waves of frequency S_2 .

In the operation of the circuit, speech current of frequencies ranging substantially from 200 to 2000 cycles is transmitted by talking into the transmitter S which modulates the radio frequency outgoing carrier wave by means of the constant current modulator system M. A tone telegraph signal may be sent by operating the key K_1 . This impresses onto the modulator M from source G a tone of frequency outside the speech frequency range, for example, about 2500 cycles. The tone may be of less amplitude than the speech signal and will, therefore, require less energy. The modulator has, as nearly as may be practical, a linear characteristic so that there will be little or no cross modulation of the speech by the tone. At both local and distant stations the circuit D of the receiver is arranged to pass the intermediate frequency and its speech and tone telegraph side bands, the frequencies of which are shifted up and down 150 cycles due to the telegraph signal sent by key K_1 . The intermediate frequency side bands extend 2500 cycles above and below the frequency of the intermediate carrier when the 2500 cycle telegraph tone is used, and extend only 2000 cycles when the telephone channel alone is in operation. Both local and distant speech and tone telegraph will be heard in the output of intermediate frequency detector IFD No. 1. The circuit F, which may be a low pass filter with cut-off at 2000 cycles, selects speech waves S_1 and S_2 and passes them to the head set s. The telegraph tone is selected by circuit H, which may be a pair of resonant coupled circuits, a highpass filter cutting off frequencies below, for example, 2300 cycles, or a band pass filter, selecting a frequency of 2500 cycles, and passed on to the head phone G_1 . By using slightly different tones, say 2400 cycles for the distant station and 2500 for the current from source G at the local station, simultaneous tone telegraphy could be accomplished by the use of suitable selective circuits at H to pick out the distant station tone and exclude the local telegraph tone. If intermodulation in the process of detection occurs between the tones and

speech currents, it is possible to overcome the detrimental effects by a suitable choice of frequencies.

The telegraph channel under the control of key K does not necessitate the use of additional radiated energy over and above that normally used for telephony while the transmitter is in use for telephony and is transmitting a carrier wave. The frequency of the transmitter oscillator O is changed when key K is closed as described but this change in carrier current does not interfere with the previously mentioned speech or tone telegraph reception, circuit D being made to pass a band of frequencies wide enough to allow for a 150 cycle shift in the intermediate frequency range. The signal due to the actuation of key K is not received at the station of origin because the local intermediate frequency oscillator U has its frequency shifted 150 cycles in the same direction as the transmitter frequency due to the closure of a short circuit about a reactance R_1 by the right armature and front contact of relay 4. When the carrier at the distant station is changed 150 cycles, however, there is a resultant 150 cycle tone in the second intermediate frequency detector IFD No. 2 of the local station. Circuit T selects the intermediate frequency carrier and is designed to prevent the transfer of speech and tone telegraph signals. Low pass filter V cuts off at frequencies above, for example 170 cycles, or may be a circuit resonant at 150 cycles. A signal will occur in the head set W_1 only when the distant station sends with its key corresponding to K which changes the carrier by 150 cycles, since in such case relay 4 at the local receiving station is not operated and reactance R_1 is not short circuited.

The telegraph channel controlled by key K_1 may be omitted from the system or may, at any time, be left inactive without in any way affecting the effectiveness of the telegraph channel controlled by key K or the telephone channel, each of which may be worked full duplex.

The novel features believed to be inherent in the invention are defined in the appended claims.

What is claimed is:

1. In a duplex wave transmission system, a source of outgoing carrier waves effective to aid in the reception of received waves, a local source of waves effective to beat with energy controlled by received waves, and a signaling element for causing equal and simultaneous changes in the frequencies of said outgoing waves and the waves produced by said local source of waves.
2. In a duplex system wherein incoming and outgoing waves beat together to produce other waves, the method of signaling which comprises producing frequency changes in

the outgoing waves to produce signals, beating waves of frequency controlled by incoming waves with locally produced waves to produce waves of different frequencies 5 to produce signals, and preventing side tone by causing equal and simultaneous changes in the outgoing and local waves.

3. The method which comprises combining wave energies to produce a wave energy 10 of beat frequency and at intervals producing equal and simultaneous changes in the frequencies of the combined energies and in such directions as to maintain the beat frequency constant.

15 4. In a signaling system, means for preventing the production of local indications as a result of signaling changes of frequency in outgoing waves which comprises means for producing signaling changes of frequency 20 in outgoing waves, means which tends to be responsive to said frequency changes for producing a local wave having a frequency corresponding at all times to said changes, and means for producing simultaneously therewith such changes in the system as will prevent the operation of said responsive means whereby the production of said local wave is prevented.

5. The method of duplex telegraphy 25 between two stations which comprises producing a signal carrier wave at one station, changing the frequency of said wave in accordance with telegraph messages, transmitting said changed frequency wave, simultaneously 30 performing a corresponding series of operations at the other station, translating, at each station, the message-bearing wave from the other station into an audible frequency wave having message 35 characteristics by steps involving beating said received frequencies with a portion of the locally-produced wave used for transmission, and preventing the message characteristic in said locally-produced wave 40 from affecting the character of said audible frequency wave.

6. The method which comprises producing a carrier wave modulated in amplitude in accordance with two independent 45 messages, and varied in frequency in accordance with two other independent messages, and selectively simultaneously deriving from said wave and receiving without interfering one with the other at least three of said messages.

7. The method of high frequency signaling comprising transmitting a carrier wave, producing an additional wave, changing the frequency of said carrier wave to transmit 50 signals and simultaneously changing the frequency of the additional wave in correspondence with the change in frequency of said carrier wave, receiving a wave having a corresponding variation of frequency, 55 beating said received wave with the wave

from additional source, and detecting said beat frequency.

8. In a system for carrier wave transmission in which signals are transmitted by modulating a high frequency carrier wave 70 in accordance with modulation frequency impulses and by changing the normal carrier frequency, the method of reception which comprises producing with the transmitted wave, a wave at the receiver having 75 corresponding modulations and frequency changes, detecting the modulations of the received wave and detecting the changes in the normal carrier frequency by causing the received wave continuously to coact 80 with a locally produced wave to produce beats, and the method of transmitting which consists in changing the frequency of the locally produced wave in correspondence with the change in the normal carrier frequency. 85

9. In the method of simultaneous telephony and telegraphy in which telephonic signals are transmitted as modulations of a carrier frequency wave, and in which telegraphic signals are transmitted by changing 90 the carrier frequency of said wave by an audible amount, the method of reception and transmission which comprises receiving the telephonic signals by demodulating a portion of the received energy, and receiving the telegraphic signals by combining a portion of the received wave with a locally produced wave, the frequency of which differs from the normal carrier by an inaudible amount, detecting said combined waves, selecting from the detected wave the frequency component corresponding to the difference between the carrier and local frequencies, and stepping down by a non-signaling wave said difference frequency to the value corresponding to the change in carrier frequency at the remote station, and changing the frequency of the non-signaling wave in correspondence with the change in the carrier frequency 100 during transmission. 105

10. The method of two-way signaling which comprises continuously transmitting in opposite directions between two communicating stations two high frequency 115 waves differing by an inaudible frequency, combining at each station the received wave with a portion of the transmitted wave from the same station to give an auxiliary difference frequency wave, changing the frequency of the transmitted wave at either station by an audible amount in accordance with a signal, detecting said signal at the other station by combining the changed auxiliary frequency wave resulting from said signaling operation with a locally produced wave having a frequency equal to the auxiliary frequency during non-signaling operation, separating from the product of the combining operation the 120 125 130

audible frequency component which is present when signals are being transmitted from the distant station, and changing the frequency of the locally produced wave at the 5 transmitting station to correspond with the change in the high frequency transmitted wave.

11. In a two-way signaling system, means at each station for transmitting a carrier 10 wave, means at each station for producing an additional carrier wave, means at the transmitting station for changing the carrier wave to transmit signals and for correspondingly changing the frequency of the 15 additional wave thereat, means at the receiving station for producing from the transmitted carrier wave a wave having corresponding signal frequency changes, and means at the receiving station for detecting 20 the beat frequency of said received carrier wave and the unchanged additional wave thereat.

12. A two-way signal transmission system comprising two communicating stations, 25 each of which comprises, in combination, a source of high frequency waves, means for changing the frequency of said source, a transmitting circuit resonant to said frequency, a receiving circuit resonant to a 30 frequency differing from said first mentioned frequency by an inaudible amount, means for combining a portion of the transmitted energy with energy received from the other station to produce an intermediate 35 frequency wave, a local source of high frequency waves related to said combining means, additional means related to said combining means and said local source and adapted to derive from the currents associ-

ated therewith an audible frequency current 40 during the intervals of changed carrier frequency, and means actuated at the transmitting station for simultaneously changing the frequency of said local source to correspond with said change in carrier frequency. 45

13. The method of signaling between two stations which comprises generating a carrier wave at each of said stations, producing amplitude modulations in each of said 50 waves in accordance with an independent message, varying each of said carrier waves in frequency in accordance with one other independent message, and selectively simultaneously deriving from said waves and receiving without interfering one with the other at least three of said messages, the receiving operation in each instance comprising the step of combining the incoming modulated carrier wave with the locally generated carrier wave to produce a modulated intermediate frequency carrier wave. 55

14. The system comprising in combination means for generating a carrier wave, means for modulating said carrier wave in amplitude in accordance with two independent messages, means for varying said carrier wave in frequency in accordance with two other independent messages, and means for selectively simultaneously deriving from said 60 carrier wave and receiving without interfering one with the other at least three of said messages. 65

In witness whereof, I hereunto subscribe my name this 22 day of December A. D., 75 1923.

JOHN F. FARRINGTON.
